PROPANE RECOVERY

Robert V. Peaslee, Arcadia, and John F. Haines, Pasadena, Calif., assignors to C. F. Braun & Co., Alhambra, Calif., a corporation of California

Application October 9, 1953, Serial No. 385,074

5 Claims. (Cl. 62—175.5)

This invention is directed to the separation of a rich hydrocarbon gas into a liquid fraction and a gaseous fraction by a process of countercurrent contact of the gas with a liquid refrigerant. The liquid fraction generally consists of propane and higher boiling hydrocarbons and is conventionally referred to as LPG (liquefied petroleum gas). The invention is also directed to a refrigerant liquid for such process.

Propane and heavier hydrocarbons are now recovered from natural gas either by absorption or refrigeration, the latter process involving chilling the gas to a temperature at which a major portion of propane and heavier hydrocarbons are liquefied while ethane and lighter hydrocarbons remain in a gaseous state. If the natural gas contains water, as is frequently the case, it becomes necessary to dry the gas before refrigeration to avoid the formation of ice and hydrocarbon hydrates at the low temperatures employed. Such preliminary drying represents not only an appreciable cost in capital equipment and processing, but is only partially satisfactory in that a temperature no lower than about -35° F. is economically practical in the subsequent refrigeration operation.

It has been proposed to accomplish rich gas refrigeration for LPG recovery by countercurrently contacting the gas with a chilled brine (U. S. Patent 2,198,142, issued to Henry N. Wade, April 23, 1940). This proposed process is alleged to eliminate need for preliminary drying because any water in the gas is absorbed in the brine refrigerant before ice or hydrate formation takes place. However, use of brine as a direct contact refrigerant in this manner is unsatisfactory in several respects. Brine is inherently limited to use at temperatures above about -25° F. since below this temperature its viscosity is so great as to prevent the operation of the process. As a consequence, LPG recovery with brine is relatively inefficient. It is not possible with brine to achieve a degree of refrigeration as low as that obtainable with the more conventional refrigeration process. In addition, brine is highly corrosive and in such a direct contact process is difficult to recover because of dilution. Concentration of diluted brine by heat is impractical because of comparatively high heat load requirements. There is no known commercial use of this proposed process.

This invention is directed to a liquid refrigerant for recovery of LPG from natural gas by countercurrent direct contact, and which refrigerant avoids and overcomes all of the objectionable features of the heretofore proposed brine refrigerant. The invention contemplates a refrigerant comprising a solution of methyl alcohol and water in which the alcohol is present in an amount of not less than 60% by volume and not more than 90% by volume. The invention also contemplates the method of recovering LPG from hydrocarbon gas, which comprises countercurrently contacting a hydrocarbon gas with a refrigerated solution of the above described composition, removing a gaseous fraction from the liquid fraction separating liquefied hydrocarbons from the solution, rechilling the separated solution and recontacting the rechilled solution with additional feed gas.

2

The composition of the refrigerant solution is critical. Solubility of hydrocarbons in the solution, settling time, i. e. the rate of separation of solution from liquefied hydrocarbons, and solution viscosity are all factors of paramount importance. Solubility of hydrocarbons in the refrigerant increases markedly at alcohol concentrations in excess of about 85% or 90%. Solution viscosity at the low temperatures employed as well as settling time increase markedly at alcohol concentrations

5 below about 60% to 70%. Settling time at the lower range of alcohol concentrations can be improved by addition of a commercially available treating or demulsifying agent, such as the mono or di-ammonium salts of petroleum sulfonic acids, oyl hydroxy stearic acid, oleic hydrogen sulfate, and benzene sulfo stearic acid. Settling agents of this type may be employed in amounts of from about 5 to about 50 parts per million parts of refrigerant. However, such an agent will not improve an unduly high viscosity which is encountered at lower alcohol concentrations. For these reasons the process is operative with an alcohol-water solution in which the alcohol is present in not less than 60% and not more than 90% by volume. Preferably, the solution has an alcohol content of between 70% and 85% since in this concentration range the various factors mentioned above are the optimum values.

The invention will be clearly understood from the following detailed description taken in conjunction with the accompanying drawings, in which:

30 Fig. 1 is a diagram of a portion of a recovery plant for carrying out the process of the invention; and Fig. 2 is a graph showing the relationship of solubility and settling time as a function of refrigerant composition.

35 The recovery plant shown diagrammatically in Fig. 1 comprises a contactor 10, which may be a conventional bubble tower. Feed gas is introduced to the contactor through a feed gas inlet line 11 opening into the lower portion of the tower and dry gas is removed through an overhead line 12. Settled refrigerant is withdrawn from the tower through a bottoms line 13 and is introduced to a surge tank 14. A return line 15 is connected from the tank 14 to the contactor at a point intermediate the bottom of the contactor and the feed gas inlet line. 40 Liquid hydrocarbon is withdrawn through a bleed line 16 from the lower portion of the tower and is pumped into a secondary settling tank 17 by means of a pump 18 located in the line 16.

45 The refrigerant surge tank 14 is connected by a line 20 through a pump 21 to a heat exchange system including first, second, third and fourth stage exchangers 22, 23, 24, 25 and from the heat exchange system through an inlet line 26 to the upper portion of the contactor.

50 Dry gas taken overhead from the contactor is fed successively through the exchangers 24 and 22.

55 A secondary refrigerant such as liquefied ethane is passed successively through exchangers 25 and 23 by means of a line 30.

60 Liquefied hydrocarbons are removed from the secondary settling tank 17 through an overhead line 34 and may be fed to a conventional deethanizer, as indicated. Alcohol-water solution is removed from the secondary settling tank 17 through a line 35 and is introduced to an alcohol recovery tower 36 where alcohol concentration is accomplished by conventional fractionation. 65 Alcohol and water are taken overhead through line 38 and returned to the refrigerant surge tank 14 (together with any required refrigerant make up) through a make up line 39. Water is removed from the lower portion of the recovery tower 36 through a line 40.

70 A typical operation of the illustrated recovery plant is as follows: Feed gas is introduced at the lower portion

of contactor 10 through the feed gas inlet line, the gas being, for example, at a temperature of approximately 90° F. and at a pressure of approximately 400 p. s. i. g. Refrigerant is introduced to the top of the contactor through the line 26, the required temperature of the refrigerant being a function of the desired recovery efficiency. In this particular example the refrigerant entering the contactor is at a temperature of approximately -70° F. The downflowing refrigerant solution mixes countercurrently with the upflowing gas, liquefying the liquefiable portions thereof and accomplishing in effect a low temperature fractionation, at the same time absorbing water from the gas.

With the described refrigerant no objectionable hydrates or ice are formed even at these very low temperatures. In the lower portion of the contactor the liquid components separate into a hydrocarbon phase and an alcohol-water phase as indicated. The alcohol-water phase is withdrawn from the bottom of the tower through the bottoms line into the surge tank 14. Any additional hydrocarbons separating from the alcohol-water phase in the surge tank are returned to the settled hydrocarbon phase in the contactor through the line 15. Under the conditions mentioned, the refrigerant withdrawn from the lower portion of the contactor is at a temperature of approximately 50° F.

Refrigerant is withdrawn from the surge tank by the pump 21 and is passed successively through the heat exchangers 22, 23, 24, and 25 to lower its temperature to approximately -70° F. as indicated. A refrigerant medium such as ethane is introduced to the exchanger 25 through the line 30 at a temperature of approximately -80° F. and from the exchanger 25 flows through exchanger 23 at a temperature of approximately -30° F. The dry gas removed from the top of the contactor is at a temperature of approximately -60° F. and passes through the exchanger 24 at approximately this temperature. The dry gas flows from the exchanger 24 through the exchanger 22 at a temperature of approximately -30° F. wherein the recycle refrigerant undergoes its first stage refrigeration, the temperature of the refrigerant being reduced from about 50° F. to about 24° F. in the first stage exchanger 22. In the second stage exchanger 23 the refrigerant temperature is dropped to about -20° F. by heat exchange with the secondary refrigerant. In the third stage exchanger 24 the refrigerant temperature is further reduced to about -33° F. by heat exchange with the dry gas, and in the fourth stage exchanger 25 it is reduced to approximately -70° F. by heat exchange with the secondary refrigerant.

The settled hydrocarbon phase in the contactor is withdrawn from it through the hydrocarbon bleed line by means of the pump 18 and introduced into the secondary settling tank 17. Any further refrigerant settling from the hydrocarbon phase in the tank 17 is withdrawn therefrom through the line 35 and introduced into the alcohol recovery tower 36, the function of which has previously been described. The hydrocarbon phase from the secondary settling tank 17 is withdrawn through line 34.

A typical hydrocarbon material balance at the processing conditions of the above described example is set forth in the following table:

The critical nature of refrigerant composition is made apparent from the graph of Fig. 2 in which hydrocarbon solubility and settling time are plotted as functions of the volume percent methanol in the water-alcohol refrigerant. Dotted line curves A and B represent plots of solubility against alcohol concentration at temperatures of -5° F. and -60° F. respectively. Solid line curves C, D, E, F and G are plots of settling time as a function of alcohol concentration at temperatures ranging from -60° F. for curve C to -5° for curve G. It becomes immediately apparent from Fig. 2 that pure methyl alcohol is totally unsatisfactory as a refrigerant, and it is equally apparent that an alcohol-water solution containing less than about 60% by volume of alcohol is equally unsatisfactory as a refrigerant. As previously mentioned, even if settling time as represented by curves C through G is reduced by means of a settling agent, the viscosity of a refrigerant containing more than about 40% by volume of water at the temperatures contemplated is such as to render the refrigerant totally unacceptable.

We claim:

1. The process of separating a hydrocarbon gas mixture into a liquid fraction and a gaseous fraction which comprises introducing the gas mixture into a region of a separating column spaced from the ends of the column, removing gaseous hydrocarbons from the top of the column, removing liquefied hydrocarbons from the bottom of the column, introducing a refrigerant into an upper part of the column and at a temperature below that of the liquid and gaseous hydrocarbons leaving the column, the refrigerant comprising a solution of methyl alcohol and water in which the alcohol is present in from about 60% to about 90% by volume, the refrigerant being added in sufficient volume to liquefy said liquid fraction as the refrigerant flows downwardly in the column countercurrently to the unliquefied hydrocarbons flowing upwardly in the column.

2. The process of separating a hydrocarbon gas mixture into a liquid fraction and a gaseous fraction which comprises introducing the gas mixture into a region of a separating column spaced from the ends of the column, removing gaseous hydrocarbons from the top of the column, removing liquefied hydrocarbons from the bottom of the column, introducing a refrigerant into an upper part of the column and at a temperature below about minus 5° F. and below the temperature of the liquid and gaseous hydrocarbons leaving the column, the refrigerant comprising a solution of methyl alcohol and water in which the alcohol is present in from about 60% to about 90% by volume, the refrigerant being added in sufficient volume to liquefy said liquid fraction as the refrigerant flows downwardly in the column countercurrently to the unliquefied hydrocarbons flowing upwardly in the column.

3. The process of separating a hydrocarbon gas mixture into a liquid fraction and a gaseous fraction which comprises introducing the gas mixture into a region of a separating column spaced from the ends of the column, removing gaseous hydrocarbons from the top of the column, removing liquefied hydrocarbons from the bottom of the column, introducing a refrigerant into an upper part of the column and at a temperature below that of the liquid and gaseous hydrocarbons leaving the column, the refrigerant comprising a solution of methyl alcohol and water in which the alcohol is present in from about 60% to about 90% by volume, the refrigerant being added in sufficient volume to liquefy said liquid fraction as the refrigerant flows downwardly in the column countercurrently to the unliquefied hydrocarbons flowing upwardly in the column.

erant comprising a solution of methyl alcohol and water in which the alcohol is present in from about 60% to about 90% by volume, the refrigerant being added in sufficient volume to liquefy said liquid fraction as the refrigerant flows downwardly in the column countercurrently to the unliquefied hydrocarbons flowing upwardly in the column, separating refrigerant from the liquefied hydrocarbons, rechilling the separated refrigerant, and returning the rechilled refrigerant to the top of the column.

4. The process of recovering LPG and higher boiling constituents from a wet hydrocarbon gas mixture which comprises introducing the gas mixture into a region of a separating column spaced from the ends of the column, introducing a refrigerant into an upper part of the column at a temperature between about minus 5° F. and minus 70° F. and below the temperature of the liquid and gaseous hydrocarbons leaving the column, the refrigerant comprising a solution of methyl alcohol and water in which the alcohol is present in from about 60% to about 90% by volume, the refrigerant being added in sufficient volume to liquefy the LPG and higher boiling hydrocarbons as the refrigerant flows downwardly in the column countercurrently to the unliquefied hydrocarbons flowing upwardly in the column, removing dry gas from an upper part of the column, separating the liquefied hydrocarbons from refrigerant in a quiescent zone at the bottom of the column, removing refrigerant, heat exchanging the removed refrigerant with dry gas and thereafter with a

second refrigerant to bring it to the temperature at which it is introduced to the column, reintroducing the refrigerant to the column, and removing liquefied hydrocarbons from the quiescent zone.

- 5 5. The process of separating a hydrocarbon gas mixture into a liquid fraction and a gaseous fraction which comprises introducing the gas mixture into a region of a separating column spaced from the ends of the column, removing gaseous hydrocarbons from the top of the column
- 10 10 and liquefied hydrocarbons from the bottom of the column, introducing a refrigerant into an upper part of the column and at a temperature between about minus 5° F. and minus 70° F. and below that of the liquid and gaseous hydrocarbons leaving the column, the refrigerant
- 15 15 comprising a solution of methyl alcohol and water in which the alcohol is present in from about 70% to about 85% by volume, the refrigerant being added in sufficient volume to liquefy said liquid fraction as the refrigerant flows downwardly in the column countercurrently to the unliquefied hydrocarbons flowing upwardly in the column.
